UNITED STATES PATENT OFFICE.

PETER CASEY, OF NEWPORT, RHODE ISLAND.

IMPROVEMENT IN BRIDLE-BITS.

Specification forming part of Letters Patent No. **159,077**, dated January 26, 1875; application filed November 7, 1874.

To all whom it may concern:

Be it known that I, PETER CASEY, of Newport, in the county of Newport and State of Rhode Island, have invented a new and useful Improvement in Bridle-Bits, of which the following is a specification:

The invention will first be fully described, and then pointed out in the claim.

Figure 1 is a view of the bit, shown partly in section. Fig. 2 shows one of the side pieces, looking from the line *xx*.

Similar letters of reference indicate corresponding parts.

A A are the side pieces of the bit. B is a stationary bar, by which the two parts A A are rigidly connected. C is the movable bar, which is the main part of the bit. The side pieces A A pass through mortises in the ends of the bar C, and the bar is fastened to the side pieces by means of set-screws D D. The side pieces are provided with one or more holes, E, which receive the ends of the set-screws, so that the bar is securely held in

place. The driving-lines are attached to the loops F F of the bar C. G is a circular groove in the bar C, which admits a portion of the stationary bar B, where the two bars are placed in contact, as when driving an orderly and well-broken horse.

With a bit constructed in this manner, if the horse is unruly it is only necessary to move the bar C to enable the driver to have complete control over him, and also to prevent the horse from running out his tongue, as many horses do when in the harness.

Having thus described my invention, I claim and desire to secure by Letters Patent—

The bar C, carrying the loops F and adjustable to any fixed point upon the side bars A, in combination with said side bars A and rigidly-connecting bar B, as and for the purpose specified.

PETER CASEY.
